UNITED STATES PATENT OFFICE.

JOHN W. FOWLER, OF BROOKLYN, NEW YORK.

DESIGN FOR A STREET-CAR DASH.

SPECIFICATION forming part of Design No. 19,254, dated August 6, 1889.

Application filed January 17, 1889. Serial No. 296,654. Term of patent 14 years.

To all whom it may concern:

Be it known that I, JOHN W. FOWLER, a citizen of the United States, residing at Brooklyn, in the State of New York, have invented and 5 produced a new and original Design for a Street-Car Dash, of which the following is a specification.

A sheet of drawings accompanies this specification as part thereof.

10 Figure 1 of these drawings represents a face view of a street-car dash embodying my said design; and Fig. 2 represents a like view of one of the dash grab-handles on a larger scale, detached.

15 Like letters refer to corresponding parts of the design in both figures.

The design relates to the configuration of what may be termed the "frame" of the dash-board; and its leading features are a central 20 arch at the top of the dash and a peculiar curvilinear shape for the dash grab-handles, comprising as a conspicuous feature a cable-twist portion.

In the drawings, A represents the central 25 arch at the top of the dash.

B represents an ornamental open-work section located immediately below the arched top rail, and C C represent what are termed "dash grab-handles" at the intersections of 30 the top of the dash with its vertical lateral edges.

D represents the dash-board.

The central arch A at the top of the dash

is considered the most important feature of the design, as it is the most conspicuous feature, and is believed to be broadly new.

The central and main portion of the open-work B conveniently comprises lettering or the like, as illustrated by "E & W 23rd street" in Fig. 1, which is obviously variable. The 40 details of this open-work form no essential part of the present design.

The peculiar shape of the dash grab-handles C, one of which is shown separately by Fig. 2, comprises a cable-twist portion *a*, Fig. 45 2, which projects outward at each lateral edge of the dash, relatively slender recurved portions *b* *c*, extending from the respective ends of said cable-twist portion, and a slender curvilinear portion *d*, connecting said portions *b* 50 and *c* and merged into both.

Details which have not been specified may be of any approved description.

Having thus described my said design, I claim and desire to patent under this specification—

1. The within-described design for a street-car dash, substantially as shown.

2. In a design for a street-car dash, the within-described shape of the dash grab-handles C, substantially as shown.

JOHN W. FOWLER.
